UNITED STATES PATENT OFFICE

ROBERT LOUIS DAIN, OF NEW YORK, N. Y.

TAPE PULLING DEVICE

Application filed May 13, 1926. Serial No. 108,775.

This invention relates to a tape pulling device or tape puller as it is commonly called. The device is adapted for use in various situations but particularly to pull a ticker tape across a projection position in the manner described in my Patent No. 1,664,772, April 3, 1928. Such devices have been operated by electric motors of the series type, a series motor being particularly advantageous because of the fact that it is subjected to a great number of starts and stops. In order to prevent excessive speed of operation of the motor and its consequent vibration, it has been the custom to insert in the motor a circuit of relatively high resistance. For example, in order to maintain a motor at a speed not exceeding 1,800 revolutions per minute, it has been customary to employ a resistance of approximately 350 ohms. While this arrangement maintains the speed of the motor below the desired maximum, nevertheless it also decreases the voltage impressed upon the motor, thus causing it to operate near the critical point. The result is that, when oil or dust is deposited upon the commutator, the motor will sometimes fail to start.

Therefore, the object of my invention is to provide a tape puller operated by a motor and so arranged that the speed may be kept below a desired maximum without reducing the impressed voltage, thereby eliminating the trouble described above. This object is achieved by inserting a shunt resistance across the armature of the motor. This resistance acts as an automatic speed regulator and by a proper choice of resistance, the speed may be maintained below the desired maximum. The speed may be further regulated by means of an adjustable resistance placed in the circuit.

A further object of my invention is to provide an arrangement of tape puller and reel, or equivalent, to receive or control the tape which shall maintain the tape at an approximately uniform tension and which shall maintain the speed of movement of the tape substantially uniform.

In the accompanying drawing in which I have shown a selected embodiment of my invention:

Figure 1 is a front elevation of a tape

puller as applied to a projector for use with a ticker tape.

Figure 2 is an end elevation of the device shown in Figure 1 as viewed from the right of that figure.

Figure 3 is a wiring diagram showing the circuit for operating the motor.

The tape 1, in the embodiment shown is ejected from a stock ticker A and formed into a loop 2, after which it is fed across the projection position indicated by a support 3, this feeding movement being achieved by a sprocket wheel 4 operated by suitable gearing from an electric motor 5. The gearing is enclosed in the casing 6 and may be of any suitable character.

After leaving the sprocket wheel 4 the tape passes around an idler roll 7 and is suitably drawn from said sprocket wheel 4, for example, as shown wherein it is wound upon a reel 8. The diameter of the rolled tape will vary and consequently the peripheral speed of the tape will increase as the diameter of the roll increases. Therefore, I have provided a slip connection between the motor and the reel, this connection being exemplified by the belt 9 which is preferably in the form of a coiled spring and which is trained over the pulleys 10 and 11. The pulley 10 may conveniently be mounted upon an extension of the shaft 12 which carries the sprocket wheel 4, and the pulley 11 is mounted upon a shaft 13 which carries at its other end the reel 8. The shaft 13 and idler roll 7 may be conveniently mounted in a frame 14 adapted to be secured to the end of the gear casing 6.

Supported in the loop 2 is an arm 15 one end of which is pivoted at 16. The arm 15 forms a switch controlling the operation of the motor 5, the pivot being connected to the conductor 17 and the arm carrying a contact 18 adapted to engage the fixed contact 19 which in turn is connected to the conductor 20. Then it is obvious that the circuit of the motor will be opened and closed by variations in the loop 2 in the manner fully set forth in my aforesaid patent. Because of the numerous startings and stoppings of the motor, a series motor is employed. In order to avoid

the disadvantages referred to above the armature 21 of the motor is shunted by the resistance 22 which is preferably fixed. The usual series winding is indicated at 23. In order to more accurately and exactly regulate the speed of the motor the adjustable resistance 24 is placed in the circuit which includes any usual source of power 25 for operating the motor.

10 In operation the resistance 22 is so selected that the amount of current passing through the armature is sufficient to give the desired maximum speed. The resistance thus acts as an automatic regulator of the speed of the motor. The speed may be further regulated as stated above by the adjustable resistance 24. The motor operates in the manner set forth in my aforesaid copending application, the switch being opened and closed 15 by variations in the loop 2. The tape is fed across the projection position by means of a tape puller and is wound upon the reel 8 at a substantially constant speed. The belt 9 will slip as the roll of tape on the reel increases 20 in diameter and, therefore, the speed of the tape remains substantially constant.

25 I am aware that various changes will occur to those skilled in the art and that such changes may be made without departing from the scope of my invention. I therefore do not intend to limit myself except by the appended claims.

I claim:

30 1. In combination, a stock ticker from which a printed tape is ejected intermittently and at an irregular rate, a projection field, a motor, means operated by said motor for pulling said tape through said projection field, a reel for receiving said tape after passage thereof beyond said means, there being a tape loop between said projection field and said ticker which changes in configuration when said ticker and the tape-pulling means operate in non-synchronous relation with respect to each other, means whereby the operation of said tape-pulling means is discontinued in response to 35 decrease in configuration of said tape loop, and means forming a driving connection between said motor and said reel, said motor, by said driving connection, rotating said reel at progressively decreasing speed as the tape roll thereon progressively increases in size.

40 2. In combination, a stock ticker from which a printed tape is ejected intermittently and at an irregular rate, a projection field, a motor, means operated by said motor for pulling said tape through said projection field, a reel for receiving said tape after passage thereof beyond said means, there being a tape loop between said projection field and said ticker which changes in configuration when said ticker and said motor operate in non-synchronous relation with respect to 45 each other, means for discontinuing the op-

eration of said motor in response to decrease in configuration of said tape loop, and means forming a driving connection between said motor and reel, said motor, by said driving connection, rotating said reel at progressively decreasing speed as the tape roll thereon progressively increases in size.

45 3. In combination, a stock ticker from which a printed tape is ejected intermittently and at an irregular rate, a projection field, a 75 motor, means operated by said motor for pulling said tape through said projection field, there being a tape loop between said projection field and said ticker which changes in configuration when said ticker and the 80 tape-pulling means operate in non-synchronous relation with respect to each other, means whereby the operation of said tape-pulling means is discontinued in response to decrease in configuration of said tape loop, and means for drawing the tape after passage thereof beyond said pulling means, the 85 operation of said drawing means being discontinued substantially coincidentally with discontinuation of operation of said pulling 90 means, and the tape section between said drawing and pulling means remaining taut.

45 4. In combination, a stock ticker from which a printed tape is ejected intermittently and at an irregular rate, a projection field, a 95 motor, means operated by said motor for pulling said tape through said projection field, there being a tape loop between said projection field and said ticker which changes in configuration when said ticker and the 100 tape-pulling means operate in non-synchronous relation with respect to each other, means whereby the operation of said tape-pulling means is discontinued in response to decrease in configuration of said tape loop, and means operated by said motor for drawing the tape after passage thereof beyond 105 said pulling means, the operation of said drawing means being discontinued substantially coincidentally with discontinuation of 110 operation of said pulling means and the tape section between said drawing and pulling means remaining taut.

50 In testimony whereof, I have affixed my signature to this specification.

ROBERT LOUIS DAINE.
